UNITED STATES PATENT OFFICE.

WILLIAM JAHNS, OF MARATHON, WISCONSIN.

GRAIN-BAG HOLDER.

1,337,134.

Specification of Letters Patent.

Patented Apr. 13, 1920.

Application filed July 6, 1918. Serial No. 243,543.

To all whom it may concern:

Be it known that I, WILLIAM JAHNS, a citizen of the United States, residing at Marathon, in the county of Marathon and 5 State of Wisconsin, have invented new and useful Improvements in Grain-Bag Holders, of which the following is a specification.

This invention relates to improvements in grain bag holders.

10 In carrying out my invention it is my purpose to produce a grain bag holder which will firmly grip the bag and which is adjustable both vertically and laterally to engage with various sizes of bags.

15 It is also my purpose to produce a grain bag holder of a comparatively simple construction wherein the bags may be easily attached thereto and firmly supported thereby and also wherein a shaking movement

20 may be imparted to the bag to settle the grain delivered therein.

Other objects and advantages of the improvement will appear in the following specification and will be pointed out with 25 particularity in the appended claims.

In the drawings, accompanying this specification there has been illustrated a simple and satisfactory exemplification of the improvement, in which,

30 Figure 1 is a perspective view showing a grain sack secured upon a holder constructed in accordance with my invention.

Fig. 2 is a top plan view, the sack being removed.

35 Fig. 3 is a front elevation of the same.

Fig. 4 is a sectional view approximately on the line 4—4 of Fig. 1.

Fig. 5 is a side elevation.

40 Fig. 6 is a sectional view approximately on the line 6—6 of Fig. 1.

Fig. 7 is a sectional view approximately on the line 7—7 of Fig. 3.

Fig. 8 is a sectional view approximately on the line 8—8 of Fig. 2.

45 Fig. 9 is a detail sectional view approximately on the line 9—9 of Fig. 3.

Fig. 10 is a perspective view of the clamp.

Fig. 11 is a perspective view of one of the jaws of the clamp.

50 The improvement contemplates the employment of a base formed of two spaced elongated pieces or beams 10 each having an oppositely disposed upstanding standard. The standards 11, while disposed near the center of the beams or foot pieces 10 are

arranged nearer one end thereof than the other end, and the longer portions of the said members 10, from the said standards, upon their upper edges are depressed as at 12. The standards 11 are connected at their 60 upper ends by a member 13 and are further supported by angle braces 14.

The inner faces of the wall of the standards 11 are provided with alining vertically disposed elongated slots 15 receiving there- 65 in the ends of a beam or plate 16 that is secured to the lower ends of side members 17 arranged in the slots 15, but extend above the standards. The members 17 provide the sides of what I will term the lower frame 70 of the device, the plate 16 provides the lower member of the frame and the upper connecting member for the sides is indicated by the numeral 18.

The sides 17, at the portions thereof re- 75 ceived in the slots 15 of the standards are provided with vertically disposed elongated openings 19, and journaled in suitable bearings provided by transverse openings in the upper ends of the standards 11, and pass- 80 ing through the said openings 19 is a shaft 20. This shaft is held against longitudinal movement by suitable collars 21 secured thereon and contacting with the outer faces of the standards 11. One end of the shaft 85 is offset providing the same with a crank 22, and secured to this crank is a link 23 that has its lower end loosely connected, as at 24 to a foot pedal 25, the inner end of which being pivotally secured as at 26 to 90 one of the foot members 10. The shaft 20 has keyed or otherwise secured thereon toothed segments 27 one of which being disposed adjacent to the inner face of each of the standards 11, while secured to the 95 plate 16 are rack bars 28 which are engaged by the toothed segments. These rack bars are guided through suitable socket members 29 secured to the connecting member 13 for the standards 11. By this ar- 100 arrangement it will be seen that a pressure upon the pedal 25, in a downward direction will cause the frame to be moved upwardly of the base of the device and a release of such pressure will permit the frame, by 105 the weight thereof resuming its initial position by dropping or gravitating downwardly in the slots 15 of the standards. The pedal, it will be thus seen serves as a 110 means for agitating the frame, and for the

sake of convenience the frame will herein-after be referred to as the lower frame section.

The upper frame section is broadly indicated by the numeral 30 and includes flat side members 31 of a size corresponding to that of the side members of the lower frame. The inner faces of the sides of the upper frame contact with the outer faces of the 5 sides of the lower frame, yokes 32 being secured on the sides 31 and surrounding the sides 17 of the lower frame. If desired the yokes may be centrally provided with anti-frictional rollers 33 received in and contacting 10 with the side walls of elongated slots 34 on the side members 17 of the lower frame.

The sides 31 of the upper frame are provided with elongated slots or openings 35 arranged in parallelism and extending longitudinally of the said sides. One of the side walls provided by each of the openings 35 is formed with or has secured thereon a toothed rack 36. Journalled in suitable bearings 37 on the top member 18 of the lower frame is a shaft 38. On this shaft is keyed or otherwise secured pinions 39 that engage with the teeth of the racks 36. The shaft projects through the openings 35 in the sides 20 of the upper frame, and in the preferred construction of the invention, as illustrated by the drawings the toothed racks are arranged nearer the outer face than the inner face of the side members, and sleeves 40 are 30 formed on the inner faces of the pinions 39, the said sleeves contacting with the opposite walls provided by the openings 35 and as a consequence the said sleeves provide a bearing support for the upper frame so that 40 the slots in the lower frame and the anti-frictional rollers on the yokes are not absolutely essential.

On one end of the shaft 38 is secured a ratchet wheel 41. The teeth of this wheel are engaged by a dog 42. The dog is formed angularly on one end of a rod 43. The rod is journalled in bearings 44 on the inner edge of the upper connecting member for the lower frame, and the inner end of the rod 50 is arranged at an angle to provide a handle 45. A spring 45' is secured to the upper connecting member of the lower frame and to the handle 45 to retain the handle in one position and the dog in engagement with the ratchet wheel. The outer or second end of the shaft 38 is provided with a crank handle 47. By this arrangement it will be seen that the upper frame may be adjusted vertically with respect to the lower frame and held in such adjustment. The release of the dog from the ratchet wheel will permit of the upper frame gravitating downwardly over the lower frame, so that proper adjustments between the frames may be readily obtained.

The side members 31 of the upper frame,

at the upper edges thereof, and upon what I will term the outer face of the device, are connected by a flat vertically disposed plate 48. This plate, upon its outer face may be formed with a longitudinal groove, and the opposite walls provided by the groove may be slotted longitudinally, or, if desired, and as illustrated by the drawings, lipped plates 49 may be secured to the outer face of the plate 48. The lips of these plates are 70 formed upon the confronting edges thereof and provide ways for the rectangular body portions 50 of the bag holding clamps. The body of each of the clamps is formed with or has secured upon its outer face a right angular bracket 51, and the lower edge of each of the brackets is depressed longitudinally from adjacent the lower edges thereof forming a U-shaped depression 52 and a U-shaped projection 53. The bracket and the ribbed 75 or corrugated lower edge thereof forms one of the jaws of the clamp. Each of the jaws is provided with a plurality of alining outwardly extending studs 54, the center stud being longer than the outer stud, and between the studs the jaw is provided with springs 55. The center and longer stud 54 has its end up set as at 56. This up set end is preferably threaded.

The outer jaw of each of the clamps comprises a flat plate 57 having openings 58 therein through which the studs project. The outer jaw is hooked by the springs 55 so that the same is normally held away from the inner jaw. The outer jaw, adjacent the lower edge thereof is depressed longitudinally from its opposite sides forming the same with an inturned U-shaped projection 59 and a U-shaped depression 60. These corrugated portions of the upper jaw are designed to 100 co-engage with corrugated portions 52 and 53 of the inner jaw when the outer jaw is brought against the inner jaw. On the upset 56 of the central stud is journalled a cam 61 having a handle 62. Preferably this cam 110 is formed of strap iron bent or coiled upon itself to provide the cam surface and the handle. It will be apparent that by operating the handle the cam 61 will be brought to contact with the outer face of the outer 115 jaw moving the same against the pressure of the springs into contact with the inner jaw. It will be further noted, by reference to the drawings that the corrugated surface of the inner jaw is disposed a considerable 120 distance below the bracket on which the said corrugated surface is formed so that ample room is provided for the edge of the sack 63 when the same is clamped between the jaws.

On the plate or connecting member for the sides of the upper frame, above the upper edge of the said plate is arranged a longitudinally disposed guide rod 65 the offset ends of which being connected to the said plate in any desired or preferred man-

ner. On the guide rod is arranged for slide-
able movement apron plates 66 and 67 re-
spectively. Each of the plates, upon its
upper edge is rounded inwardly upon itself
5 to provide the same with a barrel 68 which
is received on the guide rod 65. It is to be
noted that each of the barrels 68 is extended
from the outer end of the respective apron
plates less than one-half the length of the
10 said plate and that the plate 66 has its up-
per edge lapping the plate 67. The outer
edges of the plates are bent upon themselves
providing the plates 66 with a cross sec-
tional U-shaped groove 69 and the outer
15 edge of the plate 67 with a rib 70 which is
received in the groove 69. By this arrange-
ment a tight joint is retained between the
plates, but the said plates may be folded one
over the other, when the clamps are ad-
20 justed longitudinal of the upper frame, in a
manner which will presently be described.
The body plate of each of the clamps, or if
desired the bracket on each of the body
plates has arranged thereon a hook 71, and
25 each of the apron plates, adjacent the outer
edge thereof is provided with a slot 72 re-
ceiving the respective hooks. By this ar-
rangement the apron plates are not only
detachably connected with the clamps but
30 are retained at a desired inclination with
respect to the clamps and with respect to
the frame. The plate 66 has its inner edge
notched as at 73, the notch being arranged
in a line with the hook 71 which engages
35 the apron plate 67, so that the plate 66 can
slide to fully cover the plate 67, when the
clamps are adjusted for a very small sized
sack.

Secured to the connecting plate for the
40 sides of the upper frame is a rack 74. The
rack is extended over the end of the device
on the side thereof provided with the foot
pedal and with the crank end of the shaft
38. Preferably the rack is in the nature of
45 a flat slotted plate and one of the edges pro-
vided by the said slot is formed with the
rack teeth. In the slot of the rack plate is
arranged a lever 75, the same having a
transverse lug 76 which contacts with the
50 upper face of the rack plate to hold the
lever thereon. The lever has one of its edges
provided with an elongated inturned portion
forming a tooth 77 that is designed to
co Engage with the rack teeth. The lower
55 end of the lever is rounded inwardly and is
provided with spaced openings. The upper
opening receives the offset end of a short
link 78 which is loosely connected to the
clamp nearest the lever, while the lower
60 opening receives the offset end of a link 79
that is loosely connected to the second
clamp. The slot in the rack plate, through

which the lever passes permits of a lateral
movement of the lever to bring the tooth
thereof into or out of engagement with any 65
of the teeth of the rack, and by proper ad-
justment of the lever with respect to the
rack the tooth of the lever engaging with a
certain tooth of the rack permits of a quick
and accurate adjustment of the clamps with 70
respect to each other, and by properly ful-
cruming the lever on the tooth rack one of
the clamps may be moved toward or away
from the other without influencing the last
75 referred to clamp.

The apron properly directs the grain to
the sack preventing the same filling the
ways in which the clamps slide. By operat-
ing the foot pedal or lever the grain in the
sack will be agitated to cause the same to 80
properly gravitate to the bottom of the sack
and so level the grain in the sack. The de-
vice can be operated by a single hand, and
is portable. It is thought, from the fore-
going, when taken in connection with the 85
drawings that the construction and opera-
tion of the device will be fully understood,
and a more detailed description thereof will
not be necessitated.

Having thus described the invention, what 90
I claim is:

1. In a grain sack holder, a base, a sec-
tional frame thereon, adjusting means be-
tween the sections of the frame, agitating
means between the base and frame, longi- 95
tudinally adjustable clamps carried by said
frame, a hinged collapsible apron on the
frame between the clamps, and connecting
means between the sections of said apron
and the respective clamps. 100

2. In a grain sack holder, a base, a sec-
tional frame supported by said base, means
for reciprocating the frame, one section of
the frame having its sides lapping the sec-
tions of the other section, yokes secured to 105
the upper section and surrounding the sides
of the lower section, means carried by the
lower section and co Engaging with the up-
per section for vertically moving the latter,
stop means for said adjusting means, spaced 110
slidable clamps on the upper section, and a
collapsible apron on the frame between the
clamps.

3. In a grain sack holder, a base, a sec-
tional frame supported on said base, means 115
between said frame and base for imparting
a reciprocatory movement to the frame,
means for adjusting the sections of the
frame with respect to each other, means for
retaining said sections in alinement, clamps 120
on the upper section and a collapsible apron
between the clamps.

In testimony whereof I affix my signature.
WILLIAM JAHNS.
